UNITED STATES PATENT OFFICE.

WILLIAM LEWIS, OF UTICA, NEW YORK.

SPRING CUSHION.

Application filed May 25, 1926. Serial No. 111,531.

This invention relates to a spring cushion adapted to be used as a bed mattress or as a seat for a couch, chair, automobile, and analogous objects and involves the use of a system or systems of similar helical springs arranged vertically side by side in a substantially horizontal plane and suitably sheathed so as to form a substantially rectangular cushion.

10 The main object is to assemble and secure the springs and sheathings in such manner as to secure and maintain a more uniformly parallel relation between the lower and upper surfaces of the cushion than has heretofore been practised.

For example, in cushions of this character it has heretofore been customary to draw one or both of the opposite longitudinal edges of the cushion toward a medial plane between 20 the lower and upper faces of the central portion of the cushion thereby deflecting the upper longitudinal corners downwardly and effecting a corresponding compression of the adjacent springs and contributing in a measure to the deformation of the adjacent portions of the cushion due to the fact that those portions are usually subjected to the most severe usage and one of the specific objects of the present invention is to enable the upper ends of the longitudinal rows of springs 30 to assume practically the same level as the tops of the intermediate springs when pressure thereon is removed so that the upper surface of the cushion may retain its original 35 flat or level plane.

Another specific object is to arrange the springs in rows so that two of the rows will extend along the lengthwise edges of the cushion from end to end to be known as the 40 front and rear rows while the remaining springs will be arranged in rows transversely of the cushion between the front and rear rows to be known as the intermediate set of springs so that the springs of each of the 45 front and rear rows may act independently of each other and of the intermediate rows and thereby to assist in maintaining the keeping of the longitudinal corners of the cushion at the same level or plane as the corresponding ends of the intermediate springs

and at the same time to allow more or less independent action of the several transverse rows of springs relatively to the longitudinal rows.

Another specific object is to incorporate 55 the transverse rows in separate sheaths with portions of the sheath of each row extending along opposite sides of and between the individual springs of that row to avoid contact between the springs and at the same 60 time to allow them in parallel relation.

A further object is to sheath the entire system of springs in one complete casing and to reinforce the casing at the corners by welts or equivalent reinforcements to assist in 65 resisting deformation of the cushion.

Other objects and uses relating to specific parts of the cushion will be brought out in the following description.

In the drawings:—

Figure 1 is a perspective view, partly broken away, of a spring cushion embodying the various features of the invention.

Figures 2, 3 and 4 are enlarged sectional views taken on lines 2—2, 3—3 and 4—4 respectively, Figure 1.

As illustrated, this cushion comprises a system of similar coil or helical springs arranged vertically side by side in a horizontal plane so as to form a substantially rectangular cushion and divided into what may be termed front and rear longitudinal sets —1— and intermediate sets —2—.

The springs —1— of the longitudinal sets are arranged in parallel rows along the front 85 and rear edges of the cushion from end to end thereof while the springs —2— of the intermediate sets are arranged in parallel transverse rows between the front and rear rows of springs —1— which latter will be 90 arranged in transverse alinement with the corresponding transverse rows so as to maintain the rectangular form of the cushion.

The springs of each transverse row are incorporated in the cells of a cellular sheathing —3— consisting of lower and upper strips —3'— of burlaps or other suitable fabric of about the same width as the diameter of the springs and extending across the corresponding ends of said springs and also 100

extending along opposite sides of the springs to be stitched or otherwise secured to each other at —4— substantially midway between the ends of said springs and thereby to form 5 noiseless separators between contiguous sides of the springs to prevent contact of one with another, the outer ends of the strips being interposed between the end springs of each 10 transverse row and the adjacent springs of the outer lengthwise rows as shown more clearly in Figure 4.

It is now clear that the entire set of springs between the outer lengthwise rows is made up of separate transverse rows and that the 15 springs of each transverse row are inserted in the cells of a separate transverse sheath or cellular casing, the cells of which are open at opposite sides lengthwise of the cushion or in the direction of lengthwise of the outer 20 rows of springs to permit the insertion of the springs in the cells from either side and that the length of the cushion may be varied at will by simply adding or subtracting one or more of the transverse extending cellular 25 sheathings with the springs therein while the width of the cushion may be varied by simply varying the length of the cellular sheathings and the number of spring-receiving cells therein.

30 The cells in the transverse sheathings are of uniform length determined by the spacing of the stitchings —4— which are arranged to hold the springs under more or less compression with the lower and upper ends of the 35 cells in parallel planes uniform distances apart when the springs of each sheath are placed in the cells.

The lower and upper ends of the springs and adjacent portions of the sheathing of 40 each transverse row are tied together by cords —5— extending diametrically across the adjacent ends of the springs and secured to diametrically opposite sides of the end convolutions thereof by loops —6— of the tie members —5—, said loops being passed through the adjacent portions of the fabric and around contiguous portions of the end convolutions of the springs for holding the springs —2— of each transverse row against relative lateral 45 movement or displacement.

50 The springs —1— of the front and rear rows or sets and also the springs —2— of the intermediate transverse rows together with the cellular sheathings for said intermediate rows are housed in a casing —7— of burlaps or other suitable flexible fabric, said housing comprising lower and upper plates of sheets —8— and —8'— and opposite side or end strips or sections —9— and —9'— stitched 55 or otherwise secured together at the corners to form a hollow substantially rectangular casing or housing in which the bottom and top plates or sections —8— and —8'— are held by the side and end sections —9— and —9'— in parallel spaced relation a distance 60

apart substantially equal to the vertical height of the springs.

That is, the vertical height of the side and end strips or sections —9— and —9'— is substantially equal to the vertical depth of the 70 springs —1— and —2— when placed under the desired compression.

The areas of the top and bottom sections —8— and —8'— are substantially equal to the combined areas of the several springs 75 inclosed therein except that their marginal edges extend outwardly slightly beyond the outer edges of the outer springs while the lower and upper edges of the side and end strips or sections —9— and —9'— are flanged so outwardly at —10— to form reinforcing 80 welts which are stitched or otherwise secured to the adjacent edges of the top and bottom sections to stiffen the same and to assist in maintaining the rectangular form of the outer 85 casing in addition to strengthening the corners of said casing to resist the expansion of the springs.

As previously stated the side and end sections —9— and —9'— of the cushion serve 90 to hold the marginal edges of the lower and upper sections —8— and —8'— in parallel relation against the tension of the adjacent 95 springs and in like manner the intermediate portions of the lower and upper sections are 100 held in parallel spaced relation against the action of the intermediate springs by a series of vertically disposed webs or partitions —12— of burlaps or equivalent material extending from front to rear between the side 105 walls —9— and of about the same vertical height as the side and end walls, said webs being arranged in uniformly spaced relation parallel with the end walls —9'— so as to 110 extend between adjacent springs —1— at both sides of the cushion and also between the transverse rows of springs —2— thereby closing the inner open ends of the sheathings for the transverse rows of springs and at the same time forming noiseless cushions between the adjacent springs.

The lower and upper edges of the webs or partitions —12— are flanged laterally and stitched or otherwise secured to the adjacent portion of the bottom and top sections 115 —8— and —8'— thereby preventing the spreading of the intermediate portions of the cushion by the springs and assisting in holding said top and bottom sections in parallel spaced relation corresponding to the 120 length of the springs when placed under more or less compression as shown more clearly in Figures 2 and 3.

Suitable tie cords —13— and —14— are 125 extended diametrically across opposite ends of the outer transverse rows of springs —2— and across the inner edges of the opposite end convolutions of the side spring —1— and are stitched or otherwise secured to the adjacent portions of the bottom and top 130

sections —8— and —8'— and to the contiguous portions of the springs —1— and —2— so as to bind both ends of the side springs to the corresponding ends of the adjacent intermediate springs and also to tie opposite ends of the springs of each row to each other thereby aiding in maintaining the parallelism of the bottom and top sections and also serving to distribute the compression strains upon any one or more springs to the adjacent springs.

In making up the cushion the housing —7— may be made to the size required except that one of the side members as 9—9 15 may be left unattached along one of its longitudinal edges to permit the insertion of the springs therethrough into their respective compartments between the end walls —9— and —9'— and partitions —12—. 20 The coiled springs —1— for the back row may then be inserted into their respective compartments through the open side of the housing until properly positioned in a row at the back after which the several transverse 25 rows of springs —2— in their respective sheathings may be inserted endwise through the open side into their corresponding compartments after which the remaining front row of springs —1— may be placed through 30 the open side into their respective compartments.

What I claim is:

A spring cushion comprising a hollow substantially rectangular fabric housing having parallel transverse fabric partitions in equally spaced relation from each other and from the end walls and dividing the interior of the housing into a series of transverse compartments, a single upright coil spring in 35 each end of each compartment and having its lower and upper ends engaged respectively with the bottom and top walls of the housing, separate fabric sheathings extending forwardly and rearwardly of and within 40 said compartments between the front and rear end springs therein and independent thereof, and each provided with a plurality of pockets open at both ends adjacent the partitions, and separate upright coil springs 45 arranged in said pockets independently of the end springs, said housing being separate from and enclosing the sheathing and end springs.

In witness whereof I have hereunto set 50 my hand this 11th day of May, 1926.

WILLIAM LEWIS.
